UNITED STATES PATENT OFFICE.

KARSTEN KNUDSEN, OF CHICAGO, ILLINOIS, ASSIGNOR TO THE AMERICAN ELECTRIC VEHICLE COMPANY, OF SAME PLACE.

TRUSS-FRAME FOR ELECTRIC VEHICLES

SPECIFICATION forming part of Letters Patent No. 611,258, dated September 27, 1898.

Application filed October 20, 1897. Serial No. 655,835. (No model.)

To all whom it may concern:

Be it known that I, KARSTEN KNUDSEN, a citizen of the United States, residing at Chicago, in the county of Cook and State of Illinois, have invented a certain new and useful improvement in Truss-Frames and Reaches for Electric Vehicles, of which the following is a full, clear, concise, and exact description, reference being had to the accompanying drawings, forming a part of this specification.

My invention relates to a truss-frame and reach for electric vehicles, my object being to provide a form of frame and reach for such vehicles which, while light in construction, will be durable and possess great strength.

The frame is made from a series of tubes, which are secured together by brazing or otherwise to form a single and integral structure. In the preferred form of my invention I provide at both the front and rear ends of the frame a pair of lateral or transverse bars or tubes, which are joined by a pair of truss members or reaches, one at each side of the frame. The front and rear wheels are mounted on brackets carried upon the pairs of tubes, as are also the driving-gears. This arrangement affords a construction which, while possessing great strength, is quite light and may be manufactured at a comparatively small cost.

I have illustrated my invention in the accompanying drawings, in which—

Figure 1 is a plan view of the frame of my invention. Fig. 2 is a side view thereof. Fig. 3 is a rear view. Fig. 4 is a sectional view of the differential gears on the rear axle.

Like letters refer to like parts in the several figures.

At the rear of the frame a pair of transverse or lateral tubes or bars a a' are provided, which carry upon the ends the brackets a^2 a^3 and which also carry at intermediate points the brackets a^4 a^5 . The axle b , upon which the rear wheel b' is mounted, is journaled in the brackets a^2 a^4 , while the axle b^2 , carrying the wheel b^3 , is journaled in the brackets a^3 a^5 . Upon the tubes are also carried the brackets c c' , upon which the springs c^2 c^3 , supporting the body or box of the vehicle, are respectively supported.

At the forward end of the frame a pair of

transverse tubes or bars d d' is provided, which carry upon the ends the brackets d^2 d^3 , upon which the front wheels e e' are journaled, the axles upon which the wheels rotate being mounted to swing upon vertical axes journaled within the brackets d^2 d^3 . Extending from the front to the rear transverse tubes are reaches in the form of trusses f f' , which each comprise a tube f' , which intersects the front and rear pairs of transverse tubes and is secured thereto, and a lower tube f^2 , secured at the ends to the forward and rear transverse tubes, the vertical brace tubes or posts f^3 f^4 being provided between the longitudinal members f' f^2 of the truss.

The front spring g for supporting the forward end of the box or bed of the vehicle is journaled at the ends to brackets g' g' , carried upon the upper longitudinal tubes f' f' . Near the rear of the frame is a transverse tube h , extending between the tubes f' f' , and from the middle of this transverse tube extends the tube h' to the middle of the tube a' . From the tubes h and h' the motor-frame k is suspended. Upon the end of the armature-shaft is mounted a pinion k' , which meshes with the gear-wheel k^2 , mounted on a shaft k^3 , with a pinion k^4 meshing with the gear-wheel k^5 , carried upon the periphery of the shell k^6 , within which, Fig. 4, are journaled the bevel-pinions l l' , meshing with the bevel-gears l^2 l^3 , carried, respectively, upon the axles b b^2 . The differential gearing permits the independent rotation of the rear wheels.

When the vehicle is traveling in a direct line and the wheels are consequently moving at the same rate, the shell k^6 in its rotation rotates the bevel-gears l^2 l^3 , while the bevel-pinions l l' have no rotation about their own axes. When, however, as in turning a curve, one of the rear wheels must rotate faster than the other, the bevel-pinions l l' partake of rotation about their respective axes to accommodate the difference in rotation between the rear wheels, while still driving the rear wheels, due to the rotation of the shell carrying the bevel-pinions.

Having described my invention, what I claim as new, and desire to secure by Letters Patent, is—

1. A frame for vehicles comprising front

and rear transverse members each comprising two parallel tubes or bars lying in a horizontal plane and a pair of trussed reaches extending between and joining said transverse members, substantially as described.

2. A frame for vehicles comprising front and rear transverse members each comprising two parallel tubes or bars lying in a horizontal plane and a pair of trussed reaches extending between and joining said transverse members and each comprising a horizontal upper tube or bar and a lower tube or bar downwardly deflected at the intermediate portion and separated from the upper tube or bar by vertical posts, substantially as described.

3. A frame for vehicles comprising a pair of rear transverse members upon which the rear wheels are mounted, said members lying in a horizontal plane, a front transverse member, and a pair of trussed reaches extending between and joining said transverse members, substantially as described.

4. A frame for vehicles comprising a pair of rear transverse members, a front transverse member and a pair of trussed reaches extending between and joining the same and comprising each an upper bar or tube joining both rear transverse members and the front transverse member and a lower bar or tube joined at the ends with the front transverse member and with the rear transverse member of the rear pair and downwardly deflected at the intermediate portion and separated from the upper bar or tube by vertical posts, substantially as described.

5. A frame for vehicles comprising a rear transverse member, a pair of front transverse members lying in a horizontal plane, and a

pair of trussed reaches extending between and joining the same, substantially as described.

6. A frame for vehicles comprising a pair of rear and a pair of front transverse members and a pair of trussed reaches extending between and joining the same, and each comprising an upper tube or bar joining the four transverse members, and a lower downwardly deflected bar or tube joined at the ends to the extreme rear and forward members and separated from the upper bar or tube by vertical posts, substantially as described.

7. A frame for vehicles comprising a pair of forward and a pair of rearward transverse members and a pair of longitudinal members all joined together and lying in a common plane, and a pair of deflected longitudinal members separated from the other longitudinal members by vertical posts, substantially as described.

8. A frame for vehicles comprising front and rear transverse members each comprising two parallel tubes or bars lying in a horizontal plane and trussed reaches joining the same, and intermediate motor-supporting bars or rods, substantially as described.

9. A frame for vehicles having a pair of rear transverse members lying in a horizontal plane, brackets carried thereon for supporting the rear axles, and a differential gearing between the ends of said axles, substantially as described.

In witness whereof I have hereunto subscribed my name in the presence of two witnesses.

KARSTEN KNUDSEN.
